ELECTRICALLY LIGHTED SATCHEL

Arthur H. Taylor, Willimantic, Conn.

Application May 31, 1939, Serial No. 276,733

1 Claim. (Cl. 240—6.4)

This invention relates to electrically lighted satchels and has for an object to provide an electric light for illuminating the interior of the satchel when it is open, a source of power consisting of a conventional flashlight disposed in the bottom of the satchel and switches carried by the metal rim of the satchel connected in circuit with the flashlight, one of the switches controlling the bulb of the conventional flashlight, which is exposed through an opening in the wall of the satchel, and the other switch controlling the bulb which illuminates the interior of the satchel.

A further object is to provide an electrically lighted satchel in which the flashlight is removably held in place so that it may be quickly detached and removed through a zipper closed opening in the wall of the satchel to be available for use independent of the satchel.

A further object is to provide an electrically lighted satchel having a circuit breaker connected in the satchel illuminating bulb circuit so that if the manually operative controlling switch of the bulb is inadvertently left closed, the circuit will be opened automatically when the two parts of the metal rim come together as the satchel is being closed.

A further object is to provide an electrically lighted satchel which will be formed of a few strong, simple and durable parts which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part of this specification,

Figure 1 is a side elevation of an electrically lighted satchel constructed in accordance with the invention with parts broken away.

Figure 2 is an enlarged detail cross sectional view of one of the switches taken on the line 2—2 of Figure 1.

Figure 3 is a longitudinal sectional view taken on the line 3—3 of Figure 2 showing the switch in open position.

Figure 4 is an enlarged cross sectional view taken on the line 4—4 of Figure 1 and showing the circuit breaker.

Figure 5 is a fragmentary longitudinal sectional

view taken on the line 5—5 of Figure 4 showing the circuit breaker in operative position.

Figure 6 is a side elevation of a modified form of the invention in which the flashlight is removable and the bulb is carried by a flexible cable to permit moving the bulb to various positions in the satchel.

Figure 7 is a detail end elevation showing the flashlight lens disposed permanently in one wall of the satchel shown in Figure 6.

Figure 8 is a detail longitudinal sectional view taken on the line 8—8 of Figure 7 showing a circuit wire connected to the metal rim of the lens.

Figure 9 is a cross sectional view taken on the line 9—9 of Figure 6 showing one of the elastic bands for removably securing the flashlight in the satchel.

Figure 10 is a fragmentary cross sectional view showing the zipper located in the bottom of the satchel for permitting removal of the flashlight, instead of in the side of the flashlight as shown in Figure 9.

Figure 11 is a detail sectional view taken on the line 11—11 of Figure 8 showing one of the prongs of the metal rim for securing the lens to the satchel.

The invention will be described as applied to a satchel, but the term satchel is meant to extend to hand bags, doctors' cases, luggage, and all other containers.

Referring now to the drawings in which like characters of reference designate similar parts in the various views, 10 designates a hand satchel of the type carried by women when shopping or traveling, the same being opened and closed by the action of a two-piece frame 11 and 12 at the top, to one of the parts a handle 13 being connected. In carrying out the invention, a conventional flashlight 14, minus a lens, is disposed lengthwise on the bottom 15 of the satchel, the flashlight being urged endwise toward one end wall of the satchel through the medium of a helical spring 16 which is confined under tension between two metal discs 17 and 18 which form part of the flashlight circuit as well as part of the circuit of an electric bulb 19 which is mounted in a socket 20 carried by and insulated from one of the frame parts at the top of the satchel. The bulb is equipped with a shade 21 which reflects the light rays downwardly to illuminate the interior of the satchel when it is opened.

A lens 22 is mounted in an opening 23 formed in one end wall of the satchel through the medium of a pair of rings 24 which are disposed respectively on the inner and outer faces of the wall 25.

and are connected together by bolts 25 or similar connectors. The rings form a rim for the lens and also form part of the electric circuit of both the flashlight and the illuminating bulb, as well as functioning to locate the lens in the axis of light projection from the flashlight reflector 23.

Mounted on the frame member 12 is a switch casing 27, best shown in Figures 2 and 3, having a longitudinal slot 28 in the top through which projects a switch button 29. The button is provided on its bottom face with a U-shaped bridging switch contact 30 adapted to bridge a pair of stationary contacts 31 and 32 when the button is slid endwise to its limit of movement in the slot and close a circuit to the flashlight bulb 33. The flashlight bulb circuit comprises a metal disc 34 against which the center terminal 35 of one of the battery cells 36 is engaged, this disc engaging the center terminal 37 of the flashlight bulb 33. The outer terminal 38 of the flashlight bulb is connected to the metal reflector 26 of the flashlight, which is in electrical contact with the flanged ring 39 which holds the reflector in place. The flanged ring is in electrical contact with the inner ring 24 of the lens rim and this ring is connected by a circuit wire 40 to the stationary switch contact 31. The stationary switch contact 32 is connected by a wire 41 to a wire 42 which is common to both the flashlight circuit and the illuminating bulb circuit, and which is connected to the before mentioned metal disc 34. When the switch button 29 is moved to circuit closing position, a circuit may be traced through the center terminal of the battery cell 36, disc 34, flashlight bulb 33, reflector 26, flanged ring 39, inner ring 24, wire 40, stationary contact 31, bridging switch contact 30, stationary switch contact 32, wire 41, wire 42, metal disc 18, helical spring 16, metal disc 17, bottom flange metal disc 43 of the flashlight, conventional helical spring 44 of the flashlight and outer terminal 45 of one of the battery cells. When this circuit is closed, the flashlight bulb 33 is energized.

Also mounted on the frame member 12 is a switch which is a duplicate of the switch already described and comprises a casing 46, a switch button 47 carrying a bridging switch contact 48 adapted to bridge a pair of stationary contacts 49 and 50 when the button is slid endwise to close a circuit to the satchel illuminating bulb 19.

The illuminating bulb circuit comprises a wire 51 connected to the before mentioned wire 42 and to the stationary contact 50, a wire 52 connected to the stationary contact 49 and to the outer contact of the bulb 19, and a wire 53 connected to the center contact of the bulb and to a terminal 54 which is engaged through the insulating casting of the flashlight 14 and connected to the before mentioned metal disc 34.

When the switch button 47 is moved to circuit closing position, a circuit may be traced from the center terminal 35 of the battery cell 36, disc 34, terminal 54, wire 53, wire 52, contact 49, bridging contact 48, contact 50, and wire 42 to the metal disc 18. When this circuit is closed, the satchel illuminating bulb 19 will be energized.

In order to open the illuminating bulb circuit, should the operator inadvertently leave the controlling switch closed and then close the satchel, an automatic circuit breaker is included in the illuminating bulb circuit, as best shown in Figure 5. The wire 53 from the center contact of the bulb to the terminal 54 is split and connected in any preferred manner to a pair of terminals 55 which are in the nature of short metal cylinders

slidably disposed in a longitudinal opening 56 formed in an insulating block 57 which is secured in the member 12 of the satchel frame by pins 58 formed of insulating material. Helical springs 59 are disposed between the pins and the cylinders to normally hold the cylinders in electrical contact with each other.

The frame member 11 is provided with a substantially conical projection 60 of insulating material having a base portion 61 secured to the member in any preferred manner. The projection is of sufficient length to project in between the terminals 55 when the satchel is closed and hold the terminals separated to break the circuit through the illuminating bulb 19.

Figures 6 to 11 illustrate a modified form of the device, the essential differences over the described form being that the flashlight is removable through a zipper controlled opening in the satchel and the satchel illuminating bulb is carried on a flexible member such as a BX cable so as to be disposed at various locations to illuminate back of the partitions in the satchel.

The modified form of the invention includes a satchel 61 having a zipper 62 in one side wall near the bottom, extending from substantially end to end of the satchel to permit insertion and removal of a conventional flashlight 63. The flashlight is removably secured in place through the medium of elastic straps 64, each secured at one end to the bottom of the satchel and removably secured at the other end to the bottom of the satchel through the medium of a conventional fastener snap 65.

The satchel illuminating bulb 66 is carried on the free end of the BX cable 67 which is secured in any preferred manner to a partition 68 or to the wall of the satchel as may be desired. By bending the cable, the bulb may be lifted over the partition to illuminate on either side thereof.

In this form of the invention, the flashlight lens 69 is secured in an opening in the end wall of the satchel through the medium of a ring 70, best shown in Figure 7. The ring is provided with prongs 71 which are engaged through the material of the satchel and clinched over a retaining ring 72 for the lens, best shown in Figures 8 and 11.

The circuit for the flashlight comprises a helical spring 74 which is disposed between the metal end wall 75 and a metal disc 76 disposed on the end wall of the satchel. A circuit wire 77, common to both the flashlight and the satchel illuminating bulb is connected at one end to the disc 76 and at the opposite end is connected to one switch contact of a conventional sliding button switch 78 which is mounted on one end of the satchel handle 79 through the medium of circular clips 80. A wire 81 is connected to the other contact of the switch and is connected to the metal retaining ring 72 of the lens as best shown in Figure 8. The ring is in electrical contact with the metal retaining flanged ring 82 of the flashlight reflector 83, the reflector being in electrical contact with the outer terminal of the flashlight bulb 84. The center terminal of the bulb is in contact with a metal flanged disc 85 which is in electrical contact with the center pole 86 of one of the battery cells 87.

When the switch 78 is closed, a circuit may be traced through the wall 75, spring 74, disc 76, wire 77, switch 78, wire 81, retaining ring 72, retaining flanged ring 82, reflector 83, bulb 84, flanged disc 85, and center pole 86. When this circuit is closed, the flashlight bulb is energized.

The circuit for the satchel illuminating bulb comprises a wire 88 which is secured to the common wire 77, and enters the BX cable 67 where it is connected to the conventional socket 89 of the flashlight bulb 66. A wire 90 is also connected to the socket and is connected to one contact of a conventional sliding switch 91 which is secured to the other end of the handle through the medium of spring clips 92. The other contact 10 of this switch is connected by a wire 93 to a terminal 94 which is attached to the front elastic strap 64 and is provided on the inner face of the strap with a socket 95 which receives a ball 96 having a pin 97 which is riveted to the flanged disc 85. When the switch 91 is closed, a circuit may be traced through the metal wall 75, spring 74, metal disc 76, wire 77, wire 88, flashlight bulb 66, wire 90, switch 91, wire 93, terminal 94, flanged disc 85, and center pole 86 of one of the battery cells. When this circuit is closed, the satchel illuminating bulb 66 will be energized.

The ball and socket connection of the terminal 94 with the flanged disc 85 permits the elastic strap to be unclasped from the satchel to permit the flashlight to be removed when the zipper 62 is opened. The flashlight then may be used as a conventional flashlight controlled by its conventional switch 88.

In Figure 10, the zipper 99 is shown as disclosed in the bottom of the satchel and in this form of the invention the elastic flashlight retaining band 100 may be secured securely at both ends to the side walls of the satchel. 5

Since the operation has been described, as the description progressed, it is thought that the invention will be fully understood without further explanation.

What is claimed is:

The combination with a satchel having hinged frames forming the opening of the satchel, of a flashlight casing arranged in the bottom of the satchel and extending lengthwise thereof, a lens at the front end of the casing arranged within 15 an opening in the satchel, a reflector, a bulb and battery cells within the casing, a contact disc arranged between the central electrode of the uppermost battery cell and the bulb, a contact disc on the rear end of the satchel, a helical spring 20 arranged between the last named contact disc and the casing, a bulb carried by one of said frames for illuminating the interior of the satchel, and circuit wires electrically connected to said discs and to respective ones of said switches and 25 to respective ones of said bulbs.

ARTHUR H. TAYLOR.
